ABSTRACT: A self-expanding shell for engagement in a mine roof including a lower tubular section connected to a mine roof bolt, an upper resilient and expandable portion embodying a plurality of like, inherently resilient segments which, when expanded form a cone-shape member, the upper terminals of selected segments being extended to provide hook members, and a restraining member for holding the segments in overlapped, compressed condition, until inserted in a mine roof opening, the restraining member including a tubular member having a series of openings adapted to receive and hold the hook member, and a pin engageable with the tubular member for preventing accidental disengagement of the segment hook members from the tubular member.

SELF-EXPANDING SHELL FOR ENGAGEMENT IN MINE ROOF

OBJECTS OF THE INVENTION

This invention is an improvement of my previously granted U.S. Pat. No. 3,104,582 issued Sept. 24, 1963, and has for an object to provide a self-expanding shell of inherently resilient construction which bears on a large mine roof area projected both vertically and horizontally, to exert gripping forces on the mine roof and prevent any relative movement of the components of the mine roof under stress from tensions applied to the bolt.

Another object is to provide a self-expanding shell of the character described wherein the shell includes a plurality of like, inherently resilient segments, which segments are normally held in compressed, overlapped condition by a restraining member, for ready insertion of the shell in a mine roof opening, the restraining member being disengaged from the segments upon full insertion of the shell into the opening to permit expansion of the segments to form a cone-shape member engageable with the mine roof.

A still further object is to provide a self-expanding shell wherein selected segments of the shell are provided with hook-like extensions for interengagement with the restraining member, the restraining member being moved longitudinally of the shell upon full insertion into the mine roof opening, to permit disengagement of the hook-like extensions of the segments from the restraining member and consequent expansion of the segments under the inherent resiliency of those members.

Other objects will be manifest from the following description of the presently preferred form of the invention taken in conjunction with the accompanying drawings.

DESCRIPTION OF FIGURES OF DRAWINGS

FIG. 1 is an elevational view of the shell of the present invention prior to insertion in the mine roof opening;

FIG. 2 is a view similar to FIG. 1 showing the shell fully inserted into the mine roof opening and just prior to disengagement of the restraining member from the shell;

FIG. 3 is a view similar to FIGS. 1 and 2 showing the segments of the shell in fully expanded operative position in the mine roof opening;

FIG. 4 is a top plan view of the shell of the present invention in fully extended position;

FIG. 5 is a top plan view of the shell of the present invention showing the segments thereof in overlapped, compressed condition;

FIG. 6 is a longitudinal sectional view taken along the line 5-5 of FIG. 4, looking in the direction of the arrows; and

FIG. 7 is a perspective view of the restraining member forming a part of the present invention.

DESCRIPTION OF INVENTION

The shell of the present invention is adapted for insertion in a mine roof opening which comprises a uniformly bored portion 20 which may be reamed out by any suitable tool, the upper portion of which bore is enlarged at 22 to form a conical opening, above which the size of the bore is reduced at 24 to approximately the size of bore 20.

The shell of the present invention includes a tubular section 26, the lower terminal of which is internally threaded for engagement with the threaded terminal of a roof bolt 28. The upper portion of tubular section 26 issues into a plurality of reduced neck portions 30 the upper terminals of which are enlarged to provide elongated segments 32 which are of inherently resilient construction. The segments are so constructed and of such shape that when in the fully expanded position, illustrated to advantage in FIGS. 3 and 5, the segments lie in contiguous relationship to each other and form an upper section of substantially truncated cone-shape.

The upper terminals of alternate segments 32 are reduced and extended upwardly as indicated at 34, the terminals of

which extensions are then bent inwardly of the shell as indicated at 36. The inward extension of portion 36 is then bent downwardly to provide a hook member 38.

It is further within the contemplation of the present invention to provide a restraining member 40 for holding segments 32 of the shell in overlapped, compressed relationship to each other while it is being inserted into the mine roof opening. Restraining member 40 includes a generally tubular member which is square in cross section, and is provided with like faces 42 near the lower terminal of each of which is a substantially square window or opening 44. The height of each window or opening 44 is slightly greater than the length of hook member 38, in order to allow passage of segment hook members 38 through window 44 of the restraining member prior to insertion in the mine roof opening, and passage thereof back through window 44 when the shell is fully inserted into the mine roof opening.

In order to prevent accidental disengagement of hook members 38 of segments 32 from restraining member 40, a cotter pin 46 is passed through opposed windows 44 of the restraining member between the upper limit of the window and opposed portions 36 of the segments, which positively precludes passage of hook members 38 through window openings 44.

It will also be noted from a consideration of FIG. 2 that restraining member 40 is of a predetermined length to effect impingement of the upper limit thereof against the upper limit of the mine roof defining the mine roof opening, to effect relative longitudinal movement of the shell with respect to restraining member 40. This effects alignment of hook members 36 with windows 44 and, under the inherent resiliency of segments 32 in an outward direction, the segments will flex outwardly to form a cone-shape member complementing the shape of the conical portion 22 of the mine roof opening for gripping engagement with the mine roof.

OPERATION

In use of the device of the present invention, the shell is shipped and stored in the overlapped, compressed condition shown in FIG. 1 with the segments having hook-like members being external of the remaining segments. Just prior to insertion of the shell in mine roof opening 20, cotter pin 46 is removed, thereby permitting free passage of the shell upwardly through opening 20 into enlarged conical opening 22. Upward movement of the shell is continued until restraining member 40 abuts the upper limit of the opening 24. At this time the segments 32 are still retained in the overlapped, compressed position shown in FIG. 2, with hook members 38 located interiorly of the restraining member and engaged with the lower terminals of walls 42 to prevent expansion of segments 32.

Continued upward pressure against the mine roof bolt causes additional upward movement of the shell relative to restraining member 40 and, when hook members 38 clear the lower terminals of sides 42 of the restraining member, and are aligned with openings 44, the hook members are urged outwardly through the windows under the inherent resiliency of the segments into the position shown in FIG. 3, at which time the shell is in fully seated position in gripping engagement with the mine roof. After this occurs, restraining member 40 gravitates downwardly through the shell into lower tubular portion 26, as illustrated in dotted lines in FIG. 3.

The shell of the present invention may be made of any suitable material, a high carbon heat treated steel having been found to give optimum results. Also, the number of segments 32 of the shell may be varied, although a shell consisting of eight segments, has proven to work in a highly satisfactory manner.

I claim:

1. A self-expanding shell for engagement with a roof bolt in a mine roof opening, the shell including:
  - a. a lower fixed portion connected to the mine roof bolt;
  - b. an upper resilient portion issuing from said lower portion;

- c. said upper resilient portion embodying a plurality of segments;
  - d. said segments being flexed outwardly from said lower fixed portion to form a substantially conical member;
  - e. the upper terminals of a plurality of said segments being provided with extensions;
  - f. a restraining member engageable with the extensions of the segments when the segments are compressed, for preventing flexing of the segments prior to insertion in a mine roof opening;
  - g. said restraining member including a generally tubular member having a plurality of walls;
  - h. a window in each of said walls;
  - i. each said window receiving a portion of one of said extensions;
  - j. a portion of each of said extensions engaging an inner wall of said tubular member for maintaining said segments in compressed condition; and
  - k. means for disengaging said extensions from said tubular member after the shell is placed in the mine roof opening.
2. The self-expanding shell of claim 1, with the addition of:
- a. means for preventing accidental disengagement of said restraining member from said segments.
3. A self-expanding shell for engagement with a roof bolt in a mine roof opening, the shell including:
- a. a lower fixed portion connected to the mine roof bolt;
  - b. an upper inherently resilient portion issuing from said lower portion;
  - c. said upper resilient portion embodying a plurality of elongated segments;
  - d. said segments being flexed outwardly from said lower fixed portion to form a substantially conical member;
  - e. inwardly and downwardly directed hook-like members extending from the upper limits of a plurality of said segments;
  - f. a restraining member interposed between said hook-like members of the segments; and
  - g. said restraining member being provided with means for engaging and holding said hook-like members when the segments are compressed inwardly of the shell against the inherent resiliency thereof.
4. The self-expanding shell of claim 3, with the addition of:
- a. means engageable with said hook-like members and

- restraining member for preventing accidental disengagement thereof.
- 5. A self-expanding shell for engagement with a roof bolt in a mine roof opening, the shell including:
  - a. a lower tubular section engaged with a terminal of the roof bolt;
  - b. an upper resilient section issuing from said lower section;
  - c. said upper resilient section comprising a plurality of like, elongated segments extending upwardly from said lower section;
  - d. said segments being flexed outwardly from said lower tubular section;
  - e. the upper terminals of a plurality of said segments being provided with upwardly and inwardly directed extensions;
  - f. hooks projecting downwardly from the inner limits of said extensions;
  - g. a restraining member engaged with said hooks when said segments are compressed against the inherent resilience thereof, for insertion of the shell into a mine roof opening;
  - h. said restraining member being of tubular construction and embodying a plurality of walls;
  - i. a window in each of said walls through each of which one of said hooks passes; and
  - j. the restraining member further including removable means for holding said hooks within said tubular restraining member.
- 6. The self-expanding shell of claim 5, wherein:
  - a. at least two windows of said walls are in opposed relationship to each other, and
  - b. a pin removably inserted through opposed windows of the restraining member between the upper limit of the windows and the upper limits of said segment extensions for retaining said hooks in engagement with the inner walls of said restraining member beneath the windows.
- 7. The self-expanding shell of claim 6, wherein:
  - a. the height and width of said windows is slightly larger than the height and width of said hooks.
- 8. The self-expanding shell of claim 7, wherein:
  - a. alternate segments are provided with extensions;
  - b. said alternate segments lying externally of the segments having no extensions, when the segments are compressed into overlapping relationship.
